UNITED STATES PATENT OFFICE

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA

CAR-COUPLER MECHANISM

Application filed September 27, 1928. Serial No. 308,733.

My invention relates to car coupler mechanism and is particularly concerned with means for insuring that the lock by which the knuckle is normally retained in coupled position shall be prevented from accidentally jumping or jarring to unlocked position when in service, especially where the uncoupling device for actuating the knuckle lock is of the widely used jointed lever or 10 push-down type.

In the well-known jointed lever type of uncoupling device with which large numbers of freight cars are equipped, its fulcrum or pivot pin is so positioned that 15 the parts are only slightly out of balance about it and the inner end of the uncoupling lever may therefore be readily thrown or jolted in response to sudden vertical vibrations of the car as the latter moves along 20 uneven track. When the speed is moderate and the track is in good condition, the upward movements imparted to the inner end of the uncoupling device are not of sufficient amplitude to result in freeing the 25 knuckle locking block from the control of the means with which car couplers are usually provided for preventing the locking block from accidentally moving to unlocked position. Under severe service, however, 30 such as is due to the track being in bad condition, operation at high speed, and the use at times of freight cars in express service, the vigorous joltings to which the car bodies are subjected sometimes effects accidental up- 35 ward movement of the inner end of the uncoupling lever of sufficiently great extent to release the locking block from the control of the means by which it is normally prevented from executing an unlocking 40 movement.

As is frequently the case, there is little or no pull on the coupler knuckles at various times when the train is in motion, and if, under such conditions the locking block is 45 accidentally released from the control of the device normally preventing it from moving to unlocked position it is free to jump upward to an unlocked position since it is not then clamped between the tail of the 50 knuckle and the side wall of the coupler

head. Under such circumstances, the accidental upward movement of the locking block to lock-set position permits the knuckle to perform an uncoupling rotation permitting the train to part. The present 55 invention has for its object to provide a car coupler with simple and efficient means for preventing an uncoupling device of the jointed lever type from accidentally releasing the coupler locking block from the control of the means by which the latter is 60 normally locked in locked position.

The principal feature of the invention consists in associating the coupler lock and its lifter with an upwardly movable uncoupling lever and with a locking member for the latter, the coupler lock being formed with an upwardly and rearwardly opening recess for receiving the lower end of the lock lifter as well as the lower end of the 65 said lever locking member, the lifter being adapted to cooperate with the coupler head to lock the coupler lock in locked position and being provided with trunnions whereby it is slidably and rotatably connected to the 70 coupler lock, the uncoupling lever locking member being slidably supported at its lower end upon one of the said trunnions and being formed toward its upper end with a rearward projection or shoulder cooperating 75 with the coupler head and with the uncoupling lever to prevent the latter from accidentally releasing the lock lifter from locking cooperation with the coupler head. 80

Other features of the invention relating to 85 advantageous details of construction and combinations of parts will hereinafter appear and be pointed out in the claims.

In the drawings, Figure 1 is a plan view 90 of a car coupler embodying the invention showing its relation to an uncoupling device of the jointed lever type, adjacent portions of the car upon which it is mounted being also shown.

Figure 2 is an elevational view of the construction shown in Figure 1.

Figure 3 is a side elevational view, partly in section, of the coupler and associated uncoupling device, the parts being in the posi- 100

tions they normally occupy when the coupler is locked.

Figure 4 is a detail view, partly in elevation and partly in section, showing the positions assumed by the parts when the lever locking member has been partially raised by the accidental upward movement of the inner end of the uncoupling lever while the locking block remains in normal locked 10 position.

Figure 5 is a view corresponding to Figure 4 but showing the positions assumed by the parts when the coupler lock has been released from the control of the means by 15 which it is normally prevented from accidentally moving to unlocked position.

Figure 6 is a detail view in side elevation showing the lock lifter and the uncoupling lever locking member, these parts being in 20 normal locked relation as shown in Figure 3.

Figure 7 is a front elevation of the associated parts illustrated in Figure 6.

Figure 8 is a sectional view on the line 25 8—8, Figure 6.

Figure 9 is a sectional view on the line 9—9, Figure 6.

The invention has been shown as applied to a car coupler of the standard "D" type whose coupler head 1 houses a vertically 30 movable and rearwardly swinging lock 2 normally serving to lock the rotatable knuckle 3, the said lock being adapted to actuate the horizontally rotatable knuckle opener lever 4 to force the knuckle to open 35 position. These several parts may be of the usual standard form but, if desired and as shown in the drawings, the standard locking block may be formed below its recess 5 for receiving the lock lifter 6 with a bevelled 40 or undercut rear face 7 for cooperating with the forward undercut face 8 of a downwardly projecting lug 9 at the lower end of the lifter, as fully described in my pending application for Letters Patent of the United 45 States, Serial No. 282,446, filed June 2, 1928. It is preferred to provide the locking block 2 and its lifter 6 with the cooperating undercut faces 7 and 8 respectively instead of strictly adhering to the standard practice 50 in respect to the form of the lock and the form of the lower end of the lock lifter, because it has been found that the provision of the bevelled faces 7 and 8 effectively prevents the locking block from accidentally 55 jarring upward to unlocked position under all conditions except where an uncoupling device of the jointed lever or push-down type is associated with the coupler for the purpose of unlocking the latter, and that 60 even then the cooperating bevelled faces referred to effectively function unless the car upon which the coupler is mounted is subjected to unusually severe joltings.

Toward its lower end the lock lifter 6 is 65 provided on its rear side with an upwardly

facing inclined shoulder 10 which, when the locking block 2 is in locked position, normally stands under the usual lockdown lug 11 on the interior of the coupler head and thus serves to lock the locking block in 70 locked position. The lock lifter 6 is slidably and pivotally connected to the lock 2 by being provided with oppositely projecting trunnions 12 which extend into shouldered guideways 13 formed in the 75 lateral walls of the lifter receiving recesses 5 of the lock, one of the trunnions being somewhat longer than the other in order to support the uncoupling lever locking member. The lock lifter is thus enabled to perform a preliminary movement effecting the withdrawal of its shoulder 10 from beneath the lockdown lug 11 of the coupler head, so as to enable the locking block to perform the subsequent vertical and swinging movements necessary to cause it to assume lockset 80 position and to actuate the horizontally rotatable knuckle opener lever 4. To limit rearward movement of the lower end of the lock lifter when the parts are in normal 85 locked relation, the lifter is formed above its shoulder 10 with a face 14 adapted to engage the forward face of the lock down lug 11 on the interior of the coupler head.

To prevent the inner portion 15 of the 90 uncoupling lever member 16 from accidentally jumping upward to effect a movement of the lock lifter 6 resulting in releasing the locking block 2 from control of the lock-to-the-lock means normally provided by the 95 cooperation of the shoulder 10 of the lock lifter with the lockdown lug 11 of the coupler head, the coupler is provided with an uncoupling lever locking member 17 which is positioned at the side of the lock 100 lifter 6 and, like the latter, extends downwardly through an opening 18 in the top 105 wall of the coupler head and enters the recess 5 of the locking block. Between its ends the uncoupling lever locking member 110 17 has upon its rear face an extension or shoulder 19 which stands beneath the portion 20 of the top wall of the coupler head when the parts are in locked relation, the shoulder being spaced downwardly a short distance 115 from the top wall of the head. The lever locking member is preferably of angular form, being fashioned at its lower end with a downwardly and rearwardly inclined portion 21 which is slidably seated upon the 120 adjacent trunnion 12 of the lock lifter and which, like the shoulder 10 of the lock lifter, normally projects under the lockdown lug 11 of the coupler head.

This lower inclined portion 21, by cooperating 125 with the trunnion of the lock lifter, insures the return of the lever locking member 17 to its normal locked position whenever it is free to move under the influence of gravity. As will be seen from 130

Figure 5, the portion 21 of the member 17 is of sufficient length to prevent the lower end of the lever locking member from assuming a position in advance of the trunnions 12 in any relation which the lever locking member and lock lifter may assume. It is also to be noted that the portion 21 of the lever locking member is of such length as to prevent any possibility of the escape 10 of the lower end of the lever locking member 17 from the slot 5 of the locking block, thus preventing the member 17 from riding the top of the locking block 2 so as to prevent the parts dropping to locked position.

15 The inner end 15 of the uncoupling lever device extends through openings in the upper ends of the lock lifter 6 and lever locking member 17. The opening 22 at the upper end of the member 17 for receiving 20 the portion 15 of the uncoupling lever is preferably slightly elongated vertically so as to permit the lower inclined end portion 21 of the lever locking member to slide downwardly upon the trunnion 12, thus 25 insuring that the rearward extension or locking shoulder 19 shall stand well under the overlying portion 20 of the top wall of the coupler head when the parts are in locked relation. The elongation of the lever receiving opening 22 in the upper end of the member 17 also insures that the weight of the inner end portion 15 of the uncoupling lever shall be sustained by the lock lifter 6 in the normal locked position of the parts.

30 35 The opening 23 at the upper end of the lock lifter for receiving the portion 15 of the inner uncoupling lever member 16 is vertically elongated to permit the part 15 to have a preliminary upward or uncoupling 40 movement before it actuates the lock lifter. The lower portion of the opening 23 is constricted so as to provide front and rear upwardly extending shoulders 24 and 25 respectively which are adapted to cooperate 45 with the portion 15 of the uncoupling lever mechanism. As these shoulders normally stand on opposite sides of the inner end 15 of the uncoupling lever when the parts are in locked relation they thereby prevent the latter from being thrown to a position which would release the lever locking member 17 as a result of sudden stopping or starting 50 of the train or of severe application of brakes to reduce speed. The upper portion 55 of the lever receiving opening 23 in the lock lifter is widened as at 26 so as to extend upwardly beyond the lower constricted portion of said opening; the lower forward wall 27 of the wider part of the opening 60 being inclined to provide a slope down which the inner end 15 of the uncoupling lever may gravitate when it is free to do so after having been actuated by the trainman. The lower portion 28 of the rear wall of 65 the opening 23 preferably inclines upwardly

and forwardly so that an accidental upward movement of the inner portion 15 of the uncoupling lever device produces a slight rearward rotation of the lock lifter which results in forcing the undercut face at the 70 lower end of the latter to a position closely adjacent to the cooperating bevelled or undercut face 7 upon the rear of the locking block 2, as will be seen from Figure 4. At the upper end of the rear inclined wall 28 75 the opening in the lock lifter is formed with a shoulder or seat 29 serving to arrest upward movement of the portion 15 of the uncoupling lever device so as to prevent it from accidentally moving to the extreme 80 upper end of the widened portion of the opening 23 in the lock lifter.

When the inner portion 15 of the uncoupling lever member 16 accidentally jumps upwardly so as to bring the rearward extension or shoulder 19 of the lever locking member 17 into contact with the portion 20 of the top wall of the coupler head, the pressure of the shoulder 19 against the head tends to cause the lever locking member 17 90 to rotate forwardly around the uncoupling lever portion 15 as a center. Such rotation, which if permitted might enable the locking shoulder 19 to escape from beneath the overlying portion 20 of the coupler head, 95 is prevented by the engagement of the lower portion 21 of the lever locking member with the adjacent trunnion 12 of the lock lifter 6. The efficient performance of its function by the lever locking member 17 is thus insured.

100 The coupler locking mechanism is actuated by an uncoupling lever device of the well-known form in which a downward push on the outer end of an outer lever member 105 30 causes the inner lever member 16 to rotate so as to enable the portion 15 of the latter which engages the coupler locking mechanism to move upwardly. The two lever members, 16 and 30 respectively, are pivotally mounted at 31 on a bracket 32 secured to the car body, the inner end 33 of the outer lever member extending under the inner lever member 16 so as to impart an upward or uncoupling rotation to the latter when 110 the outer end of the lever member 30 is forced downward.

115 The unlocking of the coupler is effected by the uncoupling lever device in the usual way, except that the operator should force the outer end of the handle or lever member 30 rearwardly as he pushes it downwardly. This rearward movement, which the normal looseness of the uncoupling lever members on their pivot permits, causes the inner end 120 125 portion 15 of the lever member 16 to move initially to the extreme upper and forward end of the widened part 26 of the opening 23 in the lock lifter, thus shifting the upper end of the lever locking member 17 for- 130

wardly for a sufficient distance to withdraw its locking shoulder 19 from beneath the overlying portion 20 of the top wall of the coupler head. When the rearward extension or shoulder 19 of the lever locking member has thus been brought into registry with the opening 18 in the top wall of the coupler head the lock lifter 6 and the lever locking member 17 are free to be raised, either to cause the locking block 2 to assume lockset position or to cause it to perform the extended unlocking movement necessary to actuate the knuckle opener lever 4.

The mechanism may be assembled by inserting the lock lifter 6 through the throat of the coupler head 1 and assembling the locking block 2, knuckle opener 4, and knuckle 3 in the usual manner. When these parts have been positioned in the coupler head the locking block 2 is raised to lockset position, thus permitting the lever locking member 17 to be inserted downwardly through the opening or slot 18 in the top wall of the coupler head. After that has been accomplished the portion 15 of the inner lever member of the uncoupling device is passed through the openings therefor in the upper ends of the lock lifter 6 and lever locking member 17 and the uncoupling device is thereafter mounted upon the bracket 32 by which it is pivotally supported.

I claim:—

1. In car coupler mechanism, the combination of a coupler head, a rotatable knuckle, a lock for the knuckle, an uncoupling lever device having an upwardly movable inner end portion, and a plurality of relatively movable members movably connected to said end portion and extending therefrom downwardly into the coupler head, said lock being formed with an upwardly and rearwardly opening slot for receiving said members, one of said members being formed at its upper end with an upwardly and forwardly extending opening for receiving said end portion and being movably connected to said lock and having a shoulder adapted to cooperate with the coupler head to prevent the lock from accidentally assuming unlocked position, and the other of said members being formed with a rearwardly projecting shoulder normally extending under a wall of the coupler head to prevent accidental uncoupling movement of the said end portion and being provided at its lower end with a portion normally projecting rearwardly through said slot.

2. In car coupler mechanism, the combination of a coupler head, a rotatable knuckle, a lock for the knuckle, said lock being provided with an upwardly and rearwardly opening slot, a lock lifter extending downwardly through the top wall of the

coupler head and having at its lower end oppositely disposed trunnions for slidably and rotatably connecting said lifter to the lock, said lifter being provided at its lower end with a portion for cooperating with the coupler head to lock said lock in locked position, an uncoupling lever device having an upwardly movable inner end portion adapted to actuate said lifter member to cause the latter to move said lock to unlocked position, and a lever locking member for preventing accidental uncoupling movement of said end portion, said lever locking member having a shoulder normally extending under a part of the coupler head to prevent said end portion of the uncoupling lever device from accidentally actuating the lock lifter, and one of said trunnions extending under and engaging the lower end of said lever locking member.

3. In car coupler mechanism, the combination of a coupler head having a lock-down lug on its interior, a rotatable knuckle, a lock for the knuckle, a lock lifter extending downwardly through the top wall of the coupler head and movably connected to said lock, said lifter being provided with a shoulder normally extending under said lock-down lug to lock the lock in locked position, an uncoupling lever device having an upwardly movable inner end portion adapted to actuate said lifter member to cause said shoulder to be withdrawn from beneath said lug, and a lever locking member for preventing accidental uncoupling movement of said end portion, said lever locking member being movably connected to said end portion and being movable with respect to the lifter and having a shoulder adapted to extend under a part of the coupler head to prevent said end portion of the uncoupling lever device from accidentally actuating said lock lifter, and the lower end of said lever locking member extending under said lock-down lug of the coupler head when the parts are in normal locked relation.

4. In car coupler mechanism, the combination of a coupler head, a rotatable knuckle, a lock for the knuckle, a lock lifter extending downwardly through the top wall of the coupler head and provided at its lower end with trunnions for movably connecting it to said lock, said lifter being provided with a portion for cooperating with the coupler head to lock the lock in locked position, an uncoupling lever device having an upwardly movable inner end portion adapted to actuate said lifter member, and a lever locking member for preventing accidental uncoupling movement of said inner end portion, said lever locking member and said lifter being relatively movable and being adapted to be successively actuated by said inner end portion, said lifter being pro-

vided at its upper end with an upwardly and forwardly extending opening for receiving said inner end portion of the uncoupling lever device, and said lever locking member having at its lower end a rearwardly extending downwardly inclined portion slidably engaging one of said trunnions and being provided intermediate of its ends with a rearwardly extending shoulder 5 adapted to project under the upper wall of the coupler head to prevent said end portion of the uncoupling lever device from accidentally actuating said lock lifter.

5. In car coupler mechanism, the combination of a coupler head, a rotatable knuckle, a lock for the knuckle, said lock being provided with an upwardly and rearwardly opening slot, a lock lifter extending downwardly through the top wall of the coupler head and entering said slot, said lifter being movably connected to said lock and having a portion for cooperating with the coupler head to lock the lock in locked position, an uncoupling lever device having an upwardly movable inner end portion adapted to actuate said lifter member to move said lock to unlocked position, and a lever locking member for preventing accidental uncoupling movement of said end portion, said 20 lever locking member being provided with a shoulder adapted to cooperate with the coupler head to prevent said end portion from accidentally actuating said lock lifter, and said lever locking member being mov- 25 ably connected to said end portion and extending downwardly through the upper wall of the coupler head into the slot of said lock and having its lower end projecting rearwardly through said slot.

40 In testimony whereof I affix my signature.
